DISPENSING CONTAINER

Alfred J. Chamberlain, Wauwatosa, Wis.

Application November 14, 1935, Serial No. 49,660

13 Claims. (Cl. 221—11)

My invention relates to dispensing containers for liquids and is in the nature of an improvement on the dispensing container forming the subject matter of my Patent No. 1,903,442, granted April 11, 1933.

One of the objects of the present invention is to provide a dispensing container which possesses all of the advantages, especially in respect of pouring and venting of the container of my prior Patent No. 1,903,442 and which, in addition, provides a container top or head of such character as to preclude the trapping or retaining of rain, snow, ice, or other material and also eliminates any projections beyond the confines of the top.

Another object is to provide a container in which provision is made for the complete draining or dispensing of the entire liquid contents of the container upon tipping of the container to full pouring position.

Another object of the invention is to provide the pouring spout of the container with pouring lips designed and adapted to exert a nice control over the stream issuing from the spout.

A further object is to provide the pouring spout of the container with a combined dust cap and seal.

Another object is to provide a container having these advantages and capacities and which is simple and durable in its construction, so well balanced as to lend itself to convenient and easy manipulation and yet susceptible of economic manufacture from materials and by means of facilities ordinarily available.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in top plan showing a container constructed in accordance with the present invention;

Figure 2 is a fragmentary view in vertical section taken on line 2—2 of Figure 1, with parts shown in elevation for the sake of illustration;

Figure 3 is a similar view taken on line 3—3 of Figure 2; and

Figure 4 is a fragmentary view in horizontal section taken in the plane of line 4—4 of Figure 3 and looking in the direction of the arrows:

Referring to the drawings, the reference character C designates generally a metal container embodying the present invention. The con-

tainer C comprises a cylindrical body 5 which is closed by a suitable bottom (not shown). A separate top or head 6 is provided and is, generally speaking, in the form of an inverted cup in that it has a cylindrical body wall 7 and a top wall 8, which is flat except for a self-draining depression 9 which will be hereinafter more fully described. The lower edge of the cylindrical body 7 of the top is inter-seamed with the upper edge of the body 5 of the container as indicated at 10.

The depression 9 has a portion 11 designed to accommodate a suitable handle 12 which, when not in use, is housed within the confines of the depression but it may be swung up to vertical position and grasped to facilitate handling of the container. Beyond the handle receiving portion 11 of the depression 9 the top of the container is provided with a flat outwardly and downwardly inclined portion 13. The inclined portion 13 extends to and is continuous with the cylindrical body wall 7 so that the depression 9 is provided with an opening providing access to the depression 9 from the side of the head 6. Thus the depression 9 is made self draining when the container C is in upright position. A pouring spout 15 is provided and has an inturned flange 16 around its inner margin which is disposed flush against the inclined portion 13 around the outlet opening provided therein and is secured in this position in a manner which will be hereinafter more fully described. The pouring spout 15 is fully contained within the confines of the depression 9 and is spaced from the sides of the depression. It will be noted that any liquid tending to collect in the depression 9 will flow down the inclined bottom thereof, around the spout 15 and run off on the sides of the container. Within the container a draining trough, designated generally at 17, is provided and extends at an angle between the inner peripheral wall of the body 5 of the container and the outlet opening in the inclined portion 13 thereof. This draining trough has a bottom wall or body plate 18 which narrows toward the outlet opening and which is provided at its side edges with integral inturned side walls 19. The inner portion of the bottom wall is rounded and is angled with respect to the main portion as indicated at 20, whereby to fit snugly and flush against the adjacent portion of the body 5 of the container as shown in Figure 4 of the drawings. The walls 19 merge into each other as indicated at 21 at the upper end of the drain trough. The drain trough may

35

40

45

50

55

55

- be stamped from a piece of resilient sheet metal and, if desired, the junctures of the walls 19 and 20 may be united in any suitable way if manufacturing convenience requires splitting of the metal at these junctures. The portion of the drain trough which bears against the inclined portion 13 of the top is formed with an outlet opening which registers with the outlet opening of this portion 13.
- 10 An outlet fitting designated generally at 22 is provided and comprises a tubular body 23 projecting into the container and formed with screw threads to accommodate a closure plug 24. Integral with the outer end of the fitting 22 is a crimped or flanged formation including a double crimp or flange 25 which bears against the drain trough around the margin of its outlet opening and a spaced outer flange 26 which bears against the inturned flange 15 of the pouring spout. In 15 the assembly the flange formation 22 has the effect of seaming the outlet fitting, the drain trough and the pouring spout to the portion 13 of the container top. The dimensions of the draining trough are so determined that when this 20 interconnection afforded by the flanged formation 22 is effected the drain trough will have its portion 20 pressed firmly against the inner wall of the body 5 of the container. It should be noted that the draining trough 17 is so assembled 25 that it is symmetrically disposed with respect to a vertical plane passing through the transverse central line of the inclined portion 13 or, in other words the plane of line 2-2 of Figure 1.
- The closure plug 24 is readily removable and 30 is provided with a sealing flange 27 which serves to clamp a gasket 28 against the seat afforded by the flange 26 when the plug is turned up tightly to closed position. A finger grip 29 facilitates manipulation of the plug 24.
- 40 To insure the discharge of all of the contents from the drain trough through the outlet fitting 23 a suitable number of slots or openings 30 are provided in this outlet fitting adjacent the double flange 25.
- 45 The pouring spout 15 tapers to an outer pouring lip 31 and also its side portions adjacent the pouring lip 31 and at their upper edges are formed with integral inturned pouring lips 32 overlying and spaced from the bottom of said spout. 50 These lips 32 give a very effective control over the pouring operation and prevent splashing or spilling. They cause a well defined stream to flow out over the lip 31 when the container is tilted to dispense liquid therefrom.
- 55 A combined dust cap and seal 35 is provided and consists of a metal plate conforming generally to the configuration of the upper portion of the pouring spout. At the forward end of the cap 35, its body portion except for the side edges 60 is depressed as indicated at 36 so that the elevated edge portions 37 rest on the pouring lips 32 whereas the body of the forward portion of the plate lies in substantially the same plane as these lips 32. A retaining strip 38 is welded or otherwise secured to the depressed portion 36 of the cap 35 and has ends which project beyond the depressed portion as indicated at 39. These ends 39 are adapted to engage under the lips 32 when the cap is in position, thus aiding in holding the cap in place. The rear portion of the cap 35 has a downturned marginal flange 40 which is adapted to extend down over the rear portion of the pouring spout as illustrated to advantage in Figure 2. The rear portion of the cap 70 75 is provided with a slot or opening 41 and the flange 40 and the rear portion of the pouring spout 15 have aligned openings designated at 42 and 43, respectively. With the cap in position, a sealing wire or sealing band 44 may be passed through the openings 41, 42 and 43 and a seal 45 then associated with the ends of the sealing wire or band in the usual manner. In this way the container may be conveniently sealed and even if the seal is broken a dust cap is provided for the pouring spout.
- 10 With the construction described, the top of the container is flat except for the self-draining depression. Any water or liquid which may tend to collect in the depression 9 will flow down the inclined portion 13 and away from the container.
- 15 When the contents of the container are to be dispensed therefrom and the container is nearly full it need be tipped but slightly and yet a well defined stream will issue from the pouring spout and pass clear of the outside of the container. 20 The dispensing opening is self-venting so that there is no bubbling or gurgling.
- 25 The entire contents of the container may be readily dispensed due to the provision of the draining trough. This trough, when the container is tilted over toward the horizontal to dispense the last of the contents, is disposed in the lowermost part of the rounded body wall 5 of the container so that any liquid will pass into the trough 17 and from the trough out through the 30 outlet fitting. Due to the provision of the slots 30 even the last few drops may be dispensed.
- 35 While I have shown and described one construction in which the invention may be advantageously embodied, it is to be understood that 35 various changes in the size, shape and arrangement of the parts may be made without departing from the spirit of the invention or the scope of the subjoined claims.
- 40 The invention claimed is:
1. A dispensing container comprising a body portion having a top, said top being flat except for a depression therein, the bottom wall of the depression inclining downwardly and outwardly toward and merging with the outer surface of the periphery of the container below said top to provide the depression with a lateral opening permitting drainage therefrom to the side of the container and being provided with an outlet opening and a spout formation on the container surrounding said opening.
- 45 2. A dispensing container comprising a body portion having a top, said top being flat except for a depression therein, the bottom wall of the depression inclining downwardly and outwardly toward and merging with the outer surface of the periphery of the container below said top to provide the depression with a lateral opening permitting drainage therefrom to the side of the container and being provided with an outlet opening and a spout formation on the container surrounding said opening, said spout being contained entirely within the confines of the depression and a releasable closure for said outlet opening.
- 50 3. A dispensing container comprising a body portion, a separate top section for the container including an annular body having its lower edge inter-seamed with the upper edge of the body portion of the container, a flat upper end wall integral with the body of the top section and having a depression in one portion formed with a bottom wall inclining downwardly and outwardly to and merging with the outer surface of the periphery of the container below said top to provide the depression with a lateral opening

permitting drainage therefrom to the side of the container and provided with an outlet opening, and a spout formation within the confines of said depression and spaced from sides thereof, said 5 spout connecting with said outlet opening.

4. A dispensing container comprising a body portion having a top, said top having a portion depressed and formed with a bottom wall inclining downwardly and outwardly to the periphery of the container and provided with an outlet opening, a spout formation located in the depression, surrounding said outlet opening and secured to the container, and an internal draining trough extending at an angle between the portion of the 10 peripheral wall of the body of the container adjacent the spout and the outlet opening and secured to the container.

5. A dispensing container comprising a body portion having a top, said top having a portion depressed and formed with a bottom wall inclining downwardly and outwardly to the periphery of the container and provided with an outlet opening, a spout formation located in the depression, surrounding said outlet opening and secured to the container, and an internal draining trough extending at an angle between the portion of the peripheral wall of the body of the container adjacent the spout and outlet opening, said draining trough tapering from the peripheral wall of the container toward the outlet 25 opening.

6. A dispensing container comprising a body portion having a top, said top having a portion depressed and formed with a bottom wall inclining downwardly and outwardly to the periphery of the container and provided with an outlet opening, a spout formation located in the depression, surrounding said outlet opening and secured to the container, an internal draining trough extending at an angle between the portion of the peripheral wall of the body of the container adjacent the spout and the outlet opening, and an outlet fitting for the outlet opening interseamed with the spout, container and draining trough.

45 7. A dispensing container comprising a body portion having a top, said top having a portion depressed and formed with a bottom wall inclining downwardly and outwardly to the periphery of the container and provided with an outlet opening, a spout formation located in the depression, surrounding said outlet opening and secured to the container, an internal draining trough extending at an angle between the portion of the peripheral wall of the body of the container adjacent the spout and the outlet opening, a tubular outlet fitting having a flanged 50

formation at its outer end, said flanged formation clamping the spout and the draining trough to the bottom wall of the depression, and a closure for the outlet fitting.

8. A dispensing container comprising a body portion having a top, said top having a portion depressed and formed with a bottom wall inclining downwardly and outwardly to the periphery of the container and provided with an outlet opening, a spout formation located in the depression, surrounding said outlet opening and secured to the container, an internal draining trough extending at an angle between the portion of the peripheral wall of the body of the container adjacent the spout and the outlet opening, a 15 tubular outlet fitting having a flanged formation at its outer end, said flanged formation clamping the spout and the draining trough to the bottom wall of the depression, said outlet fitting having openings adjacent said flanged formation 20 to provide for complete draining of the draining trough when the container is being emptied, and a closure for the outlet fitting.

9. A dispensing container having a dispensing spout and provided with an internal draining 25 trough between the inner wall of the container and the dispensing spout.

10. A dispensing container having a body portion and provided with a pouring spout and a tapered draining trough having one end conforming to the internal contour of the peripheral wall of the container and secured thereto and having its other end interconnected with the spout.

30 11. A dispensing container having a pouring 35 spout provided with inturned pouring lips, in combination with a combined dust cap and seal having projections interfitting with the pouring lips, said spout of said cap having slots adapted to receive a seal.

40 12. A dispensing container having a pouring spout and provided with lateral projections and a combined dust cap and seal having projecting portions slidably interfittable with the lateral 45 projections of the spout, said spout and said cap having openings to accommodate the seal.

13. A dispensing container having a pouring spout and provided with lateral projections and a combined dust cap and seal having projecting portions slidably interfittable with the 50 lateral projections of the spout, said spout and said cap having openings to accommodate the seal, said cap also having a depending flange extending around a portion at least of the spout.

55 ALFRED J. CHAMBERLAIN.
